AWNING

George Dewey Swan, Rye, N.Y.

Application February 16, 1955, Serial No. 488,475

9 Claims. (Cl. 160—273)

This invention relates to a structurally and functionally improved awning assembly; the present teachings being not limited solely to the use of a liquid-impervious or water-resistant fabric, but being also usable with other materials, even including screen fabric.

It is a primary object of the invention to furnish a structure which will be capable of being readily shifted from inoperative or retracted position to an operative or extended condition. When so extended, a roof enclosure will, for example, be provided which will have none of the disadvantages heretofore inherent to the use of an awning structure. More especially, the fabric will be maintained in taut condition, so that an extremely pleasing appearance is presented, aside from the fact that moisture will not tend to collect or "pocket" upon the upper surface of the fabric. These results will be achieved despite the fact that the assembly may be operated with minimum effort and without it being necessary to overcome extreme conditions of tension and friction.

While this invention is applicable to awning structures of diverse types, it is particularly adaptable to porches adjoining homes and other structures. Where so disposed, it makes it feasible for the user to have a porch which may be located in different situations in, for example, the different seasons of the year; the structure being susceptible to ready erection, dismantling and transporting from one locality to another. Among further objects of the invention are those of furnishing a structure which will include relatively few parts, each individually simple and rugged in construction, and capable of assembly for furnishing a unitary structure of great economy and capable of use over long periods of time with freedom from all difficulties.

With these and other objects in mind, reference is had to the attached sheets of drawings illustrating practical embodiments of the invention, and in which:

Fig. 1 is a front elevation of a porch structure or similar enclosure, showing the awning applied thereto;

Fig. 2 is a fragmentary sectional view in enlarged scale, taken along the line 2—2 in the direction of the arrows as indicated in Fig. 1;

Fig. 3 is a transverse sectional view, taken along the line 3—3 in the direction of the arrows as also indicated in Fig. 1;

Fig. 4 is a transverse sectional view, taken along the line 4—4 in the direction of the arrows as indicated in Fig. 2;

Fig. 5 is a fragmentary plan view, taken along the line 5—5 in the direction of the arrows as indicated in Fig. 4;

Fig. 6 is a fragmentary sectional side view, showing one of the awning supports as illustrated in the preceding views;

Fig. 7 is a sectional side view of a support and with which there is associated an operating mechanism of alternative structure from that shown in the preceding views; and

Referring primarily to Figs. 1 and 2, there has been shown a structure suitable for the providing of an enclosed porch. This is to be regarded in an illustrative, rather than a restrictive, sense. That structure conveniently includes base portions or sills 10, from which upright supports 11 extend. These supports may, for example, define, together with horizontal supports 12, frames covered by screening 13 and an opening 14 within which a door is to be mounted and which door may likewise include a screen body if so desired. Especially the horizontal members 12 of the structure may be formed of sections such as 15 and 16 which are secured together by, for example, bolts 17, to provide hollow units. Tube separators 18 may encircle the bolts 17 within the elements 15 and 16. All of these supporting units may be constructed of diverse materials. It is preferred, however, to employ aluminum or aluminum composition which is extruded into final shape to thus furnish lightweight rigid units which may be economically produced.

Disposed adjacent the rear wall of the enclosure (which is conveniently the outer wall of the adjacent building) is a roller including end flanges 19. Coiled upon the latter is a web of suitable awning fabric. It is definitely preferred, according to the present teachings, to use a non-stretchable material which may have incorporated in it a desired degree of opacity. The material may also be of a character such that it is resistant to mildew and attack by insects. Such a material may conveniently be nylon, which is coated or impregnated with vinyl. The opposite ends of the roller are supported upon suitable brackets 21 affixed to the wall. A roller-actuating mechanism may be included in casing 22. It embraces any suitable and convenient design and preferably includes a worm and wormwheel drive of more or less conventional construction so as to be irreversible. A center support bracket 23 of suitable design is also secured to the supporting wall and conveniently mounts a roller 24 riding in frictional contact with the outer face of roll 20. This bracket also preferably includes a lower supporting portion which mounts pairs of carrying rollers 25 and 26 upon which roll 20 rests. Thus, it is apparent that as roll 20 turns, the pairs of rollers 25 and 26 will likewise be turned.

Supports and guides for the awning structure may be furnished by channel members 27 and 28 which extend outwardly from the wall and conveniently in a downward direction, as shown in Fig. 2. These members again are preferably formed of extruded aluminum. They each have slots adjacent their upper surfaces, which afford communication to their interiors. The material or web 29 of the awning is caused to enclose or be attached to elements having widths greater than the slots. Such elements are preferably continuous metallic tapes such as 30 and 32 in Fig. 4. The metal employed may be, for example, aluminum or stainless steel enclosed in envelopes 31 sewn or otherwise attached to the web 29. In the case of member 27 the fabric of the envelope is passed around tape or element 30 and through the slot of that member. Thus, the material will have a generally inverted T formation with the shank of this structure extending through the slot, the arms of the head bearing 65 against the inner face of the channel and the portions of the web adjacent the shank lying in face-to-face contact with the upper surface of the channel.

Members such as 28 preferably provide the end channels. In this case, the envelope is again disposed to extend into the channels. The awning material conveniently extends beyond the same in the form of a hem 33 to bear against the upper surface of member 28. At this

point it is reversed upon itself and attached to the body of the web as at 34. The strips are preferably related to the awning material in the manner specified. Thereupon, these strips enclosed in their envelopes are disposed to present their side edges to the slots in the members 27 and 28; the material of the envelopes presenting sufficient tolerance to allow of this manipulation. Accordingly, the strips may be introduced into the latter without difficulty. Then, the strips are permitted to assume positions as shown, which will prevent the web 29 from being withdrawn from the supporting members. The channel members may be quite independent of any supporting structure other than cross-bracing, which may be necessary, brackets and the surface of the wall. Otherwise, and as shown in Fig. 1, they may be continuations of the uprights 11.

Regardless of this, however, and in order to tension the material of the awning, adjusting provisions may be associated conveniently with the end channel members 28 of the assembly. According to the present teachings, a desirable form of apparatus for use in this connection will involve one or more bars 35 which are slidably retained upon the upper flange surface of member 28 and over which the awning material 29 passes. Such retention may be assured by headed pins 36 secured to member 28 and extending through slots 37 formed in the bar 35. As illustrated especially in Fig. 5, these slots extend at tangents to the longitudinal axis of the bar. Therefore, if the latter is shifted longitudinally with respect to member 28, it follows that the edge of the bar, being disposed adjacent the slot of member 28, will shift to overlap that slot to a greater or lesser extent. In its most projected condition, it will, in effect, narrow the slot. This will cause the edge of the bar to bear against the envelope 31 and thus tension the awning web. Accordingly, the latter will be drawn taut and be free from any sagging tendency. This will be especially true if the material of roll 20 embodies the characteristics aforesaid. To effect the desired shifting of bar 35, the end of a handle 38 may extend through an opening 39 in that bar. The handle is conveniently supported, as at 40, by a bolt or pin extending within the body of member 28. The lower end of the handle projects through a slot in that member. Therefore, if the lower end of the handle is swung, the bar will be shifted and the desired adjustment achieved.

Now, with a view to providing a mechanism by means of which the outer end of the awning web may be drawn downwardly over the supporting channel members, a bar 41 is conveniently secured to the free end of that web. This bar may be retained by looping the end of the fabric around the same. A cable 42 has its end secured to the bar 41 adjacent the end of the latter. As shown in Fig. 1, one each of these cables is associated with the channel member 27 adjacent the outer channel members 28. The end of the cable passes through the slot in the channel member and over pulleys 43, which are disposed adjacent the lower operative ends of these two members 27. Further pulleys or grooved wheels 44 may be provided within member 27 and serve to confine the cable. As especially illustrated in Fig. 2, the upper or inner ends of cables 42 are disposed around reels 45. The latter are affixed to the opposite ends of shaft 46 rotatably carried by brackets 47, as shown especially in Fig. 2. Shaft 46 also supports pulleys 48, which are connected by belts 49 with pulleys 50. The latter are affixed against movement with respect to rollers 25. The relationship of the parts is such that a ratio preferably exists which causes cable 42 to tend to move at a speed greater than the surface speed of web 29. Any compensation which is required as a result of this differential will be automatically taken care of by, for example, the slippage which may come into being as a consequence of the frictional engagement of rollers 25 with the surface of the web.

As is especially apparent in Fig. 2, the entrance portion to the slot provided in the upper surface of channel

member 27 may be defined by upturned guiding lips 51. These will serve to contact the outer surface of web 29 to prevent the same from being scored or damaged. Likewise, channel member 27 and 28, together with all corresponding members, may be cross-braced by transversely extending members 52, which are conveniently hollow and also extruded. Attachment between these parts may be effected by, for example, screws or bolts. Beyond the guiding lips or offset portions 51, channel members 27 may have their upper surfaces open as indicated at 54. This will permit of access to a securing element 53, by which their inner ends may be attached to the wall. If these supporting channel members require shortening, they should, of course, be severed adjacent these inner ends. In this manner, the over-all surface protected by the awning structure will be reduced. While on the subject of that structure, it will be appreciated that in lieu of awning material of the type heretofore specified, even screening material might be employed to provide the web 29. By proper operation of the parts, the corresponding web would be projected and retracted along the supports.

Regardless of the type of material employed, and with the parts assembled in the manner described, it will be assumed that it is desired to extend the awning to the position shown in Fig. 1, as well as Fig. 3. Under these circumstances, the mechanism within housing 22 will be actuated to cause roll 20, as in Fig. 2, to rotate in a clockwise direction. So moving, rollers 25 will be revolved incident to their frictional engagement with the outer surface of the roll. This will cause pulleys 50 to be rotated and, by means of the drive afforded through belts 49, a similar rotation on the part of pulleys 48. That rotation will cause shaft 46 to revolve and similarly move the cable reels 45. The latter will, under this movement, draw the cables onto their bodies. The cables pass over pulleys or rollers 44 within channel members 27. They reverse their course around pulley or roller 43 in each of the channel members. Being secured to the outer edge portion and preferably the bar 41 of web 29, they will therefore serve to draw that web downwardly over channel members 27 and 28. This movement will continue until the web is fully projected. It is to be remembered that the ratio of drive is such that the cables tend to travel slightly more rapidly than the web. Therefore, these cables will constantly maintain a tension on that web so that it will remain in snug contact with the upper surfaces of the supporting members.

When the web is extended to the desired extent, bars 35 may be shifted to adjust the transverse tension on the web. As the slots defined by the edges of these bars and the adjacent edges of channel members 28 are reduced in width, the necessary pull on web 29 is exerted. The latter will adjust itself transversely. It preferably being non-elastic as before brought out, it will quickly assume a properly taut condition. To retract the awning, a mere reversal in movement of the parts is necessary. Under these circumstances, cables 42 will be payed out, but will nevertheless maintain the inner face of the web in proper contact with the channel members. This retraction may be continued until substantially the entire web is upon the roll 20.

In lieu of the mechanism shown in Figs. 1 to 6, to assure a proper projection of the awning web, a mechanism such as is shown in Figs. 7 and 8 may be employed. In that case, the uprights indicated at 55 correspond to those heretofore identified under numerals 11 and 27. A shaft 56 carrying a suitable number of sheaves or pulleys is mounted transversely of the support 55 and within its interior. A cable is conveniently secured to the upright and passes around the sheaves mounted by a shaft 58. The latter is supported by a movable block 59 the lower end of which is attached to a spring 60. That spring, in turn, has its lower end fixed to, for example, the base portion of support 55.

The upper end of the cable 57 passes beyond shaft 56 and extends through the slot 62 formed at least in the upper end of the support 55. It is attached to, for example, the bar 41 of web 29. It will be apparent that if, conveniently, three passes of cable 57 are disposed around the sheaves or pulleys mounted by shafts 56 and 58, block 59 will travel at only one-third the speed of web 29. This will be despite the fact that the end of the cable 57 attached to the free end of the awning material will move in unison with the latter. A greater or lesser number of passes may, of course, be employed. However, with spring 60 involving a proper contractive force, it is apparent that it will constantly exert a pull on block 59, which, in turn, through cable 57, will be transmitted to web 29.

The latter will be retracted or permitted to project incident the operation of mechanism 22. As it projects, bar 41, under the pulling force exerted by cables 57, will move outwardly and downwardly. As it is retracted, a resistance will be imposed upon movement by the web 29. In the instance of the structure shown in Fig. 2, roller 25 will of course drive reels 45 through pulleys 50. Due to increasing effective diameter of the reels 45 as the cable 42 is wound there-around and the slippage capable of occurring at this point, complete compensation is achieved so that the material is maintained in taut condition. Under both conditions, that web will be maintained in firm sliding contact with the upper faces of the supporting members or channels. In all forms of construction, it will be apparent that the material of web 29 will be properly anchored against displacement with respect to the channel members. However, it may, without difficulty, slide longitudinally of those members as the operating mechanism is caused to function.

Thus, among others, the several objects of the invention as specifically aforementioned are achieved. Obviously, numerous changes in construction and rearrangements of the parts might be resorted to without departing from the spirit of the invention as defined by the claims.

I claim:

1. An awning structure including, in combination, a web of material, a channelled supporting member therefor, said web resting upon said member, means attached to said web and extending through the channel of said member to retain said web against withdrawal from said member, said web being movable longitudinally of said member, and manually adjustable means for tensioning said web in a transverse direction.

2. An awning structure including, in combination, a downwardly inclined channelled member formed with a slot in its upper surface, a web of material supportable in sliding contact with the upper surface of said member, said web having an outer end, a cable within said member and extending through the slot of the same, said cable being connected to the lower and outer end of said web, and means for moving said cable.

3. An awning structure including, in combination, a channeled member formed with a slot in its upper surface, a web of material supportable in sliding contact with the upper surface of said member, said web having an outer end, a cable within said member and extending through the slot of the same, said cable being connected to the end of said web, means for moving said cable, a flexible reinforcing strip disposed within said member,

55 60 65

means for connecting the material of said web to said strip and said connecting means extending through said slot to the exterior of said member.

4. In combination, a movably supported roll of awning material having an outer end, driving means for winding and unwinding said roll, a slotted guide and support extending away from said roll and in contact with the upper surface of which said material slides, means connected to such material and extending through said slot to bear against another surface of said guide to movably retain said material against separation therefrom, and means connected to the outer end of such material to subject the latter to tension.

5. In combination, a movably supported roll of awning material having an outer end, driving means for winding and unwinding said roll, a slotted guide and support extending away from said roll and in contact with the upper surface of which said material slides, a strip extending longitudinally of and within said guide, connecting means passing through said slot and attached to said strip whereby it is movably retained against separation from said guide, and means connected to the outer end of such material to subject the latter to tension.

6. In combination, a movably supported roll of awning material having an outer end, driving means for winding and unwinding said roll, a plurality of slotted guides and supports extending away from said roll and in contact with the upper surface of which said material slides, means connected to such material and extending through such slots to ride against another surface of said guide to movably retain said material against separation therefrom, and means for increasing and decreasing the width of the slot forming a part of at least one guide to subject the connecting means and said material to increasing and decreasing tension.

7. An awning structure including in combination a plurality of supports extending in a substantially horizontal plane and having channels with restricted entrance portions in their upper faces, a layer of material overlying said supports and carried thereby, means for shifting said material layer over said supports, retaining means riding within said supports, said material extending through the entrance portions thereof into the interior of said supports and means for connecting said material within said supports to said retaining means.

8. In an awning structure as specified in claim 7, and means associated with one of said supports for exerting a transverse strain on said material to tension the same.

9. In an awning structure as specified in claim 7, said material shifting means comprising elements extending within the channels of said supports and means connecting said elements to said material.
